UNITED STATES PATENT OFFICE

172,062

SPACE HEATING STOVE

George William Francis Richards,
Chigwell, England

Application September 21, 1953, Serial No. 26,894

Claims priority, application Great Britain
April 10, 1953

Term of patent 14 years

(Cl. D81—19)

To all whom it may concern:

Be it known that I, George William Francis Richards, a British subject, residing at Chigwell, Essex, England, have invented a new, original, and ornamental Design for a Space Heating Stove, of which the following is a specification, reference being had to the accompanying drawing, forming part thereof.

Figure 1 is a front elevation of a space heating stove showing my new design;

Figure 2 is a front perspective view thereof showing the right hand side;

Figure 3 is a left hand side view thereof;

Figure 4 is a bottom plan view thereof;
Figure 5 is a rear elevation thereof; and
Figure 6 is a front elevation thereof in open position

I claim:

The ornamental design for a space heating stove, as shown.
